UNITED STATES PATENT OFFICE.

HATTIE FAULKNER, OF INDIANAPOLIS, INDIANA, ADMINISTRATRIX OF
GEORGE S. FAULKNER, DECEASED.

STEAM-ACTUATED VALVE.

SPECIFICATION forming part of Letters Patent No. 434,080, dated August 12, 1890.

Application filed May 24, 1890. Serial No. 352,994. (No model.)

To all whom it may concern:

Be it known that GEORGE S. FAULKNER, deceased, during his lifetime a citizen of the United States, residing at Indianapolis, in the county of Marion and State of Indiana, did invent certain new and useful Improvements in Steam-Actuated Valves, of which the following is a specification.

The object of said invention is to procure a valve which will be automatically operated and which will be simple and inexpensive in construction.

Said invention relates to that class of valves which are especially adapted for use with steam-pumps.

It consists in forming in a cylindrical valve (which fits closely within a steam-chest transversely and extends nearly throughout its entire length) such a series of ports as will enable it not only to deliver steam to the main cylinder, but to itself, thus constituting it in itself substantially a piston, whereby the ports which extend through it are opened and closed.

The peculiar construction of this valve and the number and arrangement of the ports therein will be hereinafter more particularly described and claimed.

Referring to the accompanying drawings, which are made a part hereof, and on which similar letters of reference indicate similar parts, Figure 1 is a top or plan view of a steam-pump provided with said invention; Fig. 2, a side elevation of the same; Fig. 3, a longitudinal vertical sectional view, looking toward the left from the dotted lines 3 3, through the steam-chest valve and immediately adjacent parts, on an enlarged scale; Figs. 4, 5, 6, and 7, transverse vertical sectional views looking toward the right from the dotted lines 4 4, 5 5, 6 6, and 7 7, respectively, in Fig. 3; Fig. 8, a fragmentary longitudinal section on the dotted line 8 8 in Figs. 4 and 5, showing the by-paths in the body of the steam-chest cylinder and the depressions and orifices in the valve at one end, which constitutes the valve construction, whereby said cylinder or main valve is itself operated; Fig. 9, a similar view of the corresponding parts at the other end on the dotted line 9 9 in Fig. 7; Fig. 10, an under side plan of the

valve separately, and Fig. 11 a plan of the entire surface of the valve as it would appear if flattened out.

In said drawings, the portion marked A represents the pump; B, the steam-cylinder by which it is operated; C, the steam-chest; D, the valve, and E a transverse shaft by which said valve is given a slight rocking motion during the operation of the pump, as will be hereinafter explained.

The pump A and main operating-cylinder B are, or may be, of any usual or desired construction. They are not peculiar to the present invention, and therefore will not be further described herein, except incidentally in describing the invention. The piston-rod B' extends from one to the other, as is usual in pumps of this character, and secured to this piston-rod is an arm B², by which, through suitable connecting rods and arms, one of the operations of the valve is effected, as will presently be more fully described.

The steam-chest or valve-cylinder C is, as shown, cylindrical in form and contains the valve D, which, as before stated, is substantially equal in size to the internal diameter of this cylindrical steam-chest. In addition to the usual construction there are several by-paths c' c² c³ c⁴, formed in the wall of this steam chest or cylinder, (constituting, with corresponding openings in the valve, ports for operating said valve,) through two of which live steam passes to the ends of the valve, and thus operates it, and through the other two of which said steam exhausts. As in ordinary steam-engine work, the live-steam port or by-path at one end is in operation while the exhaust-steam port or by-path on the opposite end is in operation. A convenient means of forming these by-paths or ports is to drill in from the ends of the cylinder the required distance and then drill through transversely into these ports at each end. The ends of these openings will then be covered by the cylinder-heads when placed in position, and therefore the little spaces between the nearest transverse holes and the cylinder-heads (shown in Figs. 8 and 9) are useless except as a convenience in making the machine. In large machines these openings may be better cored out. In very small

machines it may be necessary to drill through from the outside of the cylinder, especially at the inner ends of these openings, and then plug the holes on the outside. This is also 5 shown in the drawings, (see Fig. 5;) but it will be understood, of course, that these are mere mechanical expedients and are not essential to the invention. A live-steam pipe C' is shown as coming in at the top of this 10 steam chest or cylinder, and an exhaust-steam pipe B³ is shown as leading from the side of the main cylinder B near its top. The valve D at its extreme ends is a solid cylinder. Inferiorly it contains a chamber D', which terminates 15 in the live-steam ports p, and a chamber D², the ends of which are exhaust-ports x. An opening O extends up through its top from the chamber D' and communicates with the live-steam pipe C', as shown 20 most plainly in Figs. 3 and 6. This opening is larger than the pipe, in order that the communication may always be free, notwithstanding the movement of the valve. So far as the live-steam and exhaust ports are concerned, they are simple and easily understood 25 to any one familiar with such matters.

Centrally at the bottom side and extending into the chamber D² is a slit S of the form shown most plainly in Figs. 10 and 11, the 30 diagonal ends s' s² of which come in contact with the arm e on the shaft E, hereinafter described, whereby this valve is rocked somewhat from side to side, as will be presently explained. In the outer surface of this valve 35 D are long narrow depressions, as shown most plainly in Figs. 10 and 11, which terminate in holes d', d², d³, and d⁴, extending through the shell of the valve into the chambers D', D², and which correspond with the by-paths 40 c' c² c³ c⁴, and, with said by-paths, form small ports and valves by which the large or main valve D is itself operated. Two of these holes d' d³, one at each end, extend through into the live-steam chamber D', while the 45 other two d² d⁴ extend through into the exhaust-steam chamber D². Small notches d⁵ and d⁶ are cut in the extreme ends of the valve, on the corners thereof, and in line with the holes d' d³, for the purpose of affording a 50 more certain ingress for the live steam into the space behind the ends of the valve, when said valve is at its extreme position nearest the heads of the steam-chest. Now supposing that the valve D is turned so that the 55 hole d' registers or is in line with the inner hole leading into the by-paths c', it will be apparent that a small amount of live steam will pass from the live-steam chamber D' by way of the corresponding depression connected therewith, through this hole and this by-path to the end of the valve, between it and the head of the steam-chest, which will have the effect to force the valve toward the other end of the steam-chest. When the valve 60 has nearly reached the end of its stroke in the other direction, the diagonal slot in the underside comes in contact with the arm e on

the shaft E, carrying the valve and throwing the hole d' (or its depression) and the hole or by-path c' out of registry, at the same time 70 throwing the hole d³ (or its depression) and the hole or by-path c³ into registry. The exhaust-steam openings d² c² are also brought into registry, and those—viz., d⁴ c⁴—which were before 75 in that condition are thrown out of registry or cut off, and this operation is continually repeated. It will be observed that this rocking motion so produced is not sufficient to interfere with the passage of the live steam to the main cylinder through its ports or the escape of exhaust-steam therefrom, but only sufficient to throw these small holes and depressions and by-paths out of registry with each other, or into registry, as the case may be. By this means, without the use of any additional 80 parts, the single cylindrical valve D is made not only to serve to open and close the exhaust and live steam ports for the main cylinder, and as a part of said ports, but also as 85 live and exhaust steam ports for itself. 90

The shaft E passes transversely through the downwardly-projecting portion cast on the under side of the steam chest or cylinder, and has mounted thereon an arm e, which extends up into the diagonal slot in the under 95 side of the valve. This arm is securely and fixedly mounted on said shaft, as shown most plainly in Fig. 5. At the outer end this shaft is connected to an arm E', which in turn is connected by a connecting-rod E² to the arm B² on the main piston-rod B'. This is so adjusted that the motion throws the arm into exactly the position which it is required for properly operating the valve. The arm E' is preferably connected to the shaft E by means 100 of a quadrant E³, and by means of this quadrant, as will be readily understood, any degree of adjustment may be effected, and the adjustment may be varied so that the valves formed by the holes d', &c., and their depressions, and the by-paths c', &c., may be thrown into or out of operation at varying periods, and the travel of the valve thus regulated. The arm e by this movement (which is given it through the rock-shaft E, which in 105 turn is driven from the piston-rod) operates to shift the valve more promptly than if it were stationary. Having this movement, it also permits the diagonal slot to be larger than if it were stationary, admitting of a 110 greater range of adjustment. There is an adjusting-slot in the arm E' at its lower end, where it connects to the rod E², as shown most plainly in Fig. 6, and thus the distance through 115 which the rock-shaft and consequently the arm e moves can also be correctly adjusted. A bolt e³, having a thumb-nut thereon, is the preferred means of connecting the quadrant E³ and the arm E', while a center-head bolt, having a nut on its outer end, is the preferred 120 means of connecting the arm E' and the connecting-rod E², all as shown most plainly in 125 Fig. 6.

Having thus fully described the said inven-

tion, what is claimed as new, and desired to be secured by Letters Patent, is—

1. In combination, a cylindrical steam-chest provided with the ordinary ingress pipe 5 and ports, and a cylindrical valve of the same diameter as the internal diameter of the steam-chest, but of somewhat less length, and provided with live and exhaust steam chambers, and a series of openings and by-paths in the 10 shell of the steam-chest and in the valve, a diagonal slot also in said valve, and an upward projection or arm adapted to engage with said slot, whereby as said valve is reciprocated by the action of the steam it is also 15 rocked by means of said arm or projection and a different set of perforations and by-paths brought into registry, substantially as set forth.

2. The combination of a cylindrical steam-chest provided with four longitudinal perforations, two at each end, one of each of which is adapted to receive live steam and the other to permit the escape of exhaust-steam, a cylindrical valve fitted within said steam-chest 25 and provided with a live-steam and an exhaust-steam chamber, depressions in the surface of said valve, and perforations extending from said depressions through into said chambers, said depressions being arranged to 30 register with the holes leading into the by-paths in the steam-chest, whereby a small amount of steam may be conducted through said depressions and openings and by-paths to the end of the valve and said valve thus 35 operated, substantially as set forth.

3. The combination of a cylindrical steam-chest having perforations and by-paths, as described, a cylindrical valve having live-steam and exhaust-steam chambers and corresponding perforations, and a diagonal slot, 40 and a transverse shaft mounted alongside said valve and connected to the mechanism

of the engine and carrying an arm which extends up into said diagonal slot, said shaft being adapted to be rocked oppositely to the 45 motion of the valve and said arm thus operated to shift the valve more promptly, substantially as set forth.

4. The combination of a cylindrical valve having supplementary ports, whereby it is 50 itself operated, a diagonal slot therein, a rock-shaft having an arm whereby said valve is rotated, a quadrant on the shaft carrying said arm, and an arm adjustably connected to said quadrant and also connected to the moving 55 part of the machine, whereby the movement of said shaft and of the arm engaging with the valve may be adjustably determined, substantially as set forth.

5. The combination of a cylindrical steam-chest having longitudinal perforations or by-paths extending in from its ends parallel with the valve-opening therein, said by-paths communicating at either end with said valve-opening, and a valve fitted in said valve-opening 65 and provided with a live-steam chamber and an exhaust-steam chamber, and having longitudinal depressions on its outer surface adapted to alternately register with the openings communicating with said by-paths, and 70 means whereby said valve may be rocked to cause the ports or depressions in its surface to alternately register first with one set of by-paths and then with the other, substantially 75 as described, and for the purpose specified.

In witness whereof I have hereunto set my hand and seal, at Indianapolis, Indiana, this 21st day of May, A. D. 1890.
